UNITED STATES PATENT OFFICE

LUDWIG EBERT, OF NEW YORK, N. Y.

DESIGN FOR A DISPLAY SIGN

Application filed August 26, 1930. Serial No. 36,767. Term of patent 3½ years.

To all whom it may concern:

Be it known that I, LUDWIG EBERT, a citizen of the United States, and resident of New York, in the county of New York and State of New York, have invented a new, original, and ornamental Design for a Display Sign, of which the following is a specification, reference being had to the accompanying drawings, forming part thereof.

Figure 1 is a perspective view of a display sign, showing my new design.

Fig. 2 is a left hand end view of the display sign.

I claim:

The ornamental design for a display sign, as shown.

LUDWIG EBERT.
